(57) **CLAIM**

The ornamental design for a bag, as shown and described.

DESCRIPTION

FIG. 1 is a top, front, right perspective view of a bag showing our new design; and,
FIG. 2 is a top view thereof.

The even-length broken lines within the shaded area represent stitching. The uneven-length broken lines represent unclaimed boundaries of the claimed design. The even-length broken lines showing the remainder of the bag represent unclaimed subject matter and form no part of the claimed design.
